UNITED STATES PATENT OFFICE

STEPHEN JOHN CONNOLLY, OF BEVERLY, MASSACHUSETTS, ASSIGNOR TO THE BENEVOLENT AND PROTECTIVE ORDER OF ELKS OF THE UNITED STATES OF AMERICA, OF CHICAGO, ILLINOIS, A CORPORATION OF DISTRICT OF COLUMBIA

DESIGN FOR A BADGE

Application filed January 31, 1931. Serial No. 38,508. Term of patent 14 years.

To all whom it may concern:

Be it known that I, STEPHEN JOHN CONNOLLY, a citizen of the United States, residing at Beverly, in the county of Essex and State of Massachusetts, have invented a new, original, and ornamental Design for Badge, of which the following is a specification, reference being had therein to the accompanying drawings.

In the accompanying drawings:

Figure 2 is a side elevation of the badge. The marginal edge of the badge is in gold as well as the marginal edge of the star and the antlers are also in gold. The word "Antlers" is in gold with a purplish-blue background and the star is in red.

I claim:

The ornamental design for a badge as shown and described.

In testimony whereof I hereunto affix my signature.
